UNITED STATES PATENT OFFICE.

HARRISON A. SELFRIDGE, OF NEW HAVEN, CONNECTICUT, ASSIGNOR, BY DIRECT AND MESNE ASSIGNMENTS, TO THE DURAFORM COMPANY, INCORPORATED, OF NEW HAVEN, CONNECTICUT, A CORPORATION OF CONNECTICUT.

PAPER-FOLDING MACHINE.

Application filed June 5, 1923, Serial No. 643,599. Renewed October 1, 1925.

To all whom it may concern:

Be it known that I, HARRISON A. SELFRIDGE, a citizen of the United States, residing at New Haven, in the county of New Haven and State of Connecticut, have invented a new and useful Improvement in Paper-Folding Machines; and I do hereby declare the following, when taken in connection with the accompanying drawings and the characters of reference marked thereon, to be a full, clear, and exact description of the same, and which said drawings constitute part of this application, and represent in—

Fig. 1 a plan view of a paper folding machine constructed in accordance with my invention.

Fig. 2 a front view of the same.

Fig. 3 a right-hand end view of the same.

Fig. 4 a left-hand end view of the same.

Fig. 5 a view in vertical section on the line 5—5 of Fig. 2.

Fig. 6 an enlarged, sectional view of the clamping-members and folding-slides.

Fig. 7 an enlarged, broken, sectional view on the line 7—7 of Fig. 3.

The invention relates to improvements in paper folding machines, and particularly to machines for folding paper for use in connection with pleating fabric and of a type similar to the machine shown and described in U. S. Patent No. 1,429,049, granted to me September 12, 1922. The machine of my prior patent was operated by hand, the operator being required to watch each fold, so as to know whether it should be up or down. This machine, consequently, required constant attention and special care that the folds should be made in the right direction.

The object of this invention is to provide a machine for folding paper for the purpose mentioned which shall be automatic in action, and the invention consists in the construction as hereinafter described and particularly recited in the claims.

In carrying out my invention, I employ an upper clamping-member 10, fixed at opposite ends to uprights 11 forming a part of a frame 12, and a lower movable-member 13 guided by guide-studs 14 extending down through the uprights 11. It will be noted that in this case the upper member is fixed and the lower member is movable, instead

of the reverse arrangement, as in the previous patent. The adjacent faces of these 55 clamping-members are provided with face-plates 15, which are replaceable in case of breakage. The clamping-member is moved vertically by links 16 connected with levers 17 mounted on a tie-rod 18 and provided at 60 its outer ends with rollers 19 engaging with cams 20 on a main-drive shaft 21, which is operated by a driving-pulley 22. Against the front face of the upper clamping-member 10 is a top folding-slide 23, and against 65 the front face of the lower guide is a corresponding folding-slide 24. These slides are connected together at their ends by coupling-plates 25, and the outer faces of these plates have lugs 26, to the opposite sides of which 70 operating pitmen 27 and 28 are pivotally connected, and formed at their lower ends with sockets 29 and 30. The pitmen differ in length for the purpose as will hereinafter appear. The main shaft is provided at each 75 end with eccentrics 31 and 32, and on the eccentrics 31 are collars 33 and on the eccentrics 32 are corresponding collars 34, these collars being adapted to be moved into or out of the sockets 29 or 30 by a shifting-rod 80 35, which is provided with shifting-yokes 36 and 37, the arms 38 of which enter annular grooves 39 in the collars 33 and 34, so that the collars are moved from right to left, or vice versa, according to whether the folding- 85 slides are to be moved up or down, but they are so arranged that they do not both engage at the same time.

Sliding on the shifting-rod 35 is an arm 40, mounted upon two slides 41 and 42, 90 reciprocating in a bracket 43 and in the right-hand end of the frame. For the purpose of yieldingly coupling the arm to the shifting-rod 35, helical springs 44 and 45 are arranged, one between one side of the 95 rod and the fixed collar 46, and the other between the opposite side of the rod and the right-hand yoke 36. The slides 41 and 42 are provided with inner, cam-engaging arm 47 and outer engaging-arm 48, adapted to 100 be respectively engaged by cams 49 and 50 arranged on the opposite side of a cam-plate 51 mounted on a shaft 52 carrying, at its opposite end, a sprocket 53 connected by a sprocket-chain 54 with a sprocket 55 on the 105 main-shaft 21.

The cams 49 and 50 determine when the shifting of the collars shall take place and hence whether the fold is to be up or down.

To prevent the shifting from taking place except when the collars are in line with their respective sockets, I mount a collar 56 on the rod 35, to be held by a latch 57 tripped by a pin 58 on the driving-shaft 21. It will be understood that the main-shaft 21 and shaft 52 are timed four to one, so that the shaft 21 makes four revolutions to each turn of the cam-plate 51, or one revolution for each of the four cams mounted thereon.

The stock to be folded is fed between idler feed-rolls 59 and driven feed-rolls 60 on a shaft 61, keyed to the outer end of which is a large ratchet-wheel 62 engaged by a pawl 63 mounted in the upper end of a lever 64 carried by a gear 65 loosely mounted on the shaft 61 and meshing with an intermediate gear 66 engaged by a longitudinally-movable rack 67 carrying a cam-plate 68 to be engaged by rollers 69 carried in blocks 70 adjustably mounted in slots 71 in a feed-plate 72 mounted on the shaft 52. The end of the shaft 52 has four keyways 73, while the disk 72 has a single key 74 adapted to engage with either one of the keyways 73 for the purpose of adjustment in the timing of the machine for certain forms of folding.

As indicated in the drawings, a machine is arranged for knife pleating, that is, to make alternate up and down folds in the paper and, as shown, in the position where it has just completed the up bend and is about to be shifted for the down fold, that is, the collars 34 are engaged with the sockets 30, while the collars 33 are out of engagement with the sockets 29, and in this position the spring 45 has been placed under tension by one of the cams 50, and the pin 58 is about to trip the latch 57 to permit the spring 45 to move the rod 35 to the right. When the revolution of the shaft 21 has been completed, the latch is released and the collar 34 is moved out of engagement with the socket 30 and at the same time the collars 33 are moved into engagement with the sockets 29.

50 The folding slides are then moved downward, as indicated in Fig. 6, giving the strip of paper a downward fold. It will be understood that just prior to the downward movement of the slides, the lower clamping-
55 member is moved upward, so as to clamp the strip between them, and when they retire, the clamping-members are separated to permit the paper to be fed between them by engagement of one of the rollers 69 with the
60 cam 49. At the next quarter turn of the cam-disk, the operation will be repeated to shift back the next cam on the opposite side of the plate, which will act to move the slide to the left and compress the spring 45,
65 which will exert a tendency to shift in the

opposite direction and return the parts to the position shown in Fig. 7, ready for an up bend.

In case the folds are to be made other than regularly up and down, this may be accomplished by the arrangement of the cams on the cam-disk, as in box-pleating. 70

In case it is desired to form a box-pleat between knife pleats, the key is withdrawn from one keyway and held in its retired position, so that the shaft 52 is not turned until the desired number of similar folds have been formed in the strip, when the key will be again inserted into the keyway, to continue with the knife-pleating. The strip is fed at each revolution of the main-shaft, the length of feed being determined by the position of the rollers 69 in the slots 71. It will thus be seen that for straight knife-pleating and straight box-pleating, the machine may be set and will continue to make the folds in the proper direction until the strip is completed and with but slight attention to the time that it shall take place to shift from one style of pleating to another in the same strip.

It is obvious, without further illustration, that folding means other than the particular form of slides illustrated may be employed. 85

I claim:

1. A folding machine comprising two clamping members between which the material to be folded is intermittently and automatically fed, folding means adjacent thereto consisting of two folding members adapted to be automatically moved in opposite directions across the path of the material to be folded, and connections between the said clamping members and folding means for fineing their co-action.

means for timing their co-action.

2. A paper folding machine, comprising clamping-means, one of which is movable toward and away from the other, folding slides adapted to be moved beyond the meeting-faces of said clamping-members, said slides coupled together at opposite ends, two pitmen at each end, each provided with a socket, a driving-shaft, collars on said driving-shaft adapted to be moved in or out of said sockets, yokes connected with said collars, a shifting-rod on which said yokes are mounted, and means, including a cam-disk, for moving said shifting-rod.

3. A paper folding machine, comprising clamping-means, one of which is movable toward and away from the other, folding slides adapted to be moved beyond the meeting-faces of said clamping-members, said slides coupled together at opposite ends, two pitmen at each end, each provided with a socket, a driving-shaft, collars on said driving-shaft adapted to be moved in or out of said sockets, yokes connected with said collars, a shifting-rod on which said yokes are 139

mounted, an arm on said shifting-rod, a slide with which said arm is connected, and a cam-disk adapted to move said slide in opposite directions.

5. A paper folding machine, comprising clamping-means, one of which is movable toward and away from the other, folding slides adapted to be moved beyond the meeting-faces of said clamping-members, said

10 slides coupled together at opposite ends, two pitmen at each end, each provided with a socket, a driving-shaft, collars on said driving-shaft adapted to be moved in or out of said sockets, yokes connected with said collars, a shifting-rod on which said yokes are mounted, an arm on said shifting-rod, a slide with which said arm is connected, a cam-disk adapted to move said slide in opposite directions, and springs on said shifting-rod tending to move the yokes in opposite directions.

5. A paper folding machine, comprising clamping-means, one of which is movable toward and away from the other, folding

25 slides adapted to be moved beyond the meeting-faces of said clamping-members, said slides coupled together at opposite ends, two pitmen at each end, each provided with a socket, a driving-shaft, collars on said driving-shaft adapted to be moved in or out of said sockets, yokes connected with said collars, a shifting-rod on which said yokes are mounted, an arm on said shifting-rod, a slide with which said arm is connected, a cam-disk adapted to move said slide in opposite directions, springs on said shifting-rod tending to move the yokes in opposite directions, a latch to lock the shifting-rod against longitudinal movement, and means

40 carried by said driving-shaft for tripping said latch.

6. A paper folding machine, comprising a fixed clamping-member and a movable clamping-member, means for moving the movable-member, feed-rolls in line with said clamping-members, means for giving one of said feed-rolls a predetermined movement at predetermined times, including a slotted disk with rollers mounted thereon, adapted to engage with a cam through which the said feed-roll is turned, folding slides adapted to be moved up or down beyond the meeting-faces of said clamping-members, a cam-disk shaft on which said slotted disk is mounted, means for adjusting the position of the disk on said cam-shaft, a cam-disk on said cam-shaft adapted to move said folding slides at predetermined times and in predetermined times and in predetermined directions, a driving-shaft and means connected therewith for driving said cam-shaft.

In testimony whereof, I have signed this specification.

HARRISON A. SELFRIDGE.
